UNITED STATES PATENT OFFICE.

WILLIAM N. STEVENS, OF HARTFORD, CONNECTICUT.

DIMENSIONING APPARATUS.

952,588.

Specification of Letters Patent. Patented Mar. 22, 1910.

Application filed June 8, 1909. Serial No. 500,873.

To all whom it may concern:

Be it known that I, WILLIAM N. STEVENS, a citizen of the United States, residing at Hartford, in the county of Hartford and 5 State of Connecticut, have invented a new and useful Improvement in Dimensioning Apparatus, of which the following is a specification.

This invention relates to an apparatus 10 which is designed to be used in connection with a lathe or similar cutting tool, or with a grinder or the like reducing machine, for causing the reduction of the stock to cease when the exact predetermined dimension is 15 reached.

In the type of this class of apparatus which is illustrated a feeling member, mounted upon a movable support, is brought into contact with the stock to be reduced. 20 This support is adjusted so that when the stock with which the feeling member is engaged, becomes reduced to the desired dimension by grinding or cutting, the feeler automatically operates to bring into action, 25 either an electrical, pneumatic or mechanical mechanism, which causes the advance or further action of the reducing agent or tool to cease.

The object of the present invention is to 30 provide an apparatus of this nature with means whereby changes in the relation of the feeling point to the scale by means of which the adjustment of the support is read, due to wear and to irregularities of manufacture, breakage and replacing of parts, 35 and other causes, may be compensated for in order to insure a constant reading on the dial, scale or dimension indicating device, which is utilized in adjusting the carriage, 40 to determine the necessary adjustment to stop the action of the reducing means, and thus insure very accurate dimensioning.

The invention is illustrated as embodied in an apparatus having an oscillatory feeler, 45 which, when the stock is reduced to the predetermined dimension, closes an electric circuit that sets into operation the mechanism which stops the feed of the reducing means. The feed stopping mechanism is not illustrated, as it forms no part of the present invention, and the invention is not limited to electrical means for stopping the feed of the reducing agent, as the apparatus herein described and claimed is usable for setting 50 into operation a pneumatic or a mechanical feed stop.

Figure 1 of the accompanying drawings shows a side elevation of an apparatus which embodies the invention, with parts broken away in order to better illustrate the construction. Fig. 2 shows a plan of the same apparatus with parts broken away and cut in section. Fig. 3 shows a transverse section on the plane indicated by the dotted line 3-3 on Fig. 2.

While the invention is applicable for dimensioning work of various shapes, held in machines of different types, it is illustrated in the drawings and described herein in connection with the reduction of a cylindrical 70 piece of stock 1, by means of a grinding or polishing wheel 2. This stock is represented as supported by ordinary centers 3, mounted in the head and tail stocks of a common machine.

The base 4 of the dimensioning apparatus is mounted on the top of a portion of the table 5 of the machine, in such manner that it may be moved longitudinally along the table parallel with the stock to be reduced 80 to the necessary position opposite the stock for the feeler to engage therewith. Mounted on one end of the base is a block 6, which holds a threaded feed spindle 7. This spindle at its outer end has a wheel 8 provided 85 with a handle 9, by means of which the feed screw may be rotated. The periphery of the hand wheel is provided with a scale 10, the graduations of which are spaced any desired distance apart, and attached to the 90 spindle bearing block is an index arm 11 with a zero mark 12 adjacent to the edge of the scale on the periphery of the hand wheel.

On the top of the base of this apparatus is a dove-tailed way 13, and mounted on this way so that it may be moved toward and from the stock to be reduced, is a feeler support or carriage 14. A nut 15, which fits the feed screw, is rotatably mounted in one end of this carriage. This nut has a head 16, by means of which it may be turned, when the clamp lever 17 is loosened so as to release it. When the clamp lever is tightened, the nut is held against rotation. On a beveled collar 18 of the nut is a scale 19, the graduations of which are designed to be read in connection with the zero point 20 on the plate 21 that is fastened to the end of the carriage. On the side of the carriage is a scale 22. This scale is held in place by 105 the clamps 23, and is preferably graduated in fractions of inches. Secured to the base 110

is an arm 24, the upper end of which is provided with a zero point 25, designed to register with the graduations of the scale on the side of the carriage.

15 The feeler lever 26 is mounted on a pivot 27 carried at the front of the support or carriage. The lower end of the short arm of this lever is provided with a feeling point 28 made of a suitably hard substance. The 20 upper end of the long arm of the feeler lever is provided with a thumb screw 29. Pivotally mounted on ears 30 in the housing on the top of the carriage below the feeler lever is a contact lever 31. This contact lever has 25 a contact point 32 that is arranged to engage with the fixed contact point 33 when the contact end of the lever is pressed down. When the contact end of the lever is free, the other end of the lever being the heavier, 30 causes a disengagement of the contacts. A circuit wire 34 is shown as connected with the contact lever 31, and a circuit wire 35 is shown as connected with the fixed contact 33. These circuit wires are designed 35 to be connected with the apparatus which stops the feed or causes a cessation of the effective action of the reducing tool or agent, whatever it may be.

In using this apparatus, after it has been 20 moved along the top of the table to a position opposite the piece of stock to be reduced to the predetermined dimension, the hand wheel is turned and the feed screw rotated so as to move the feeler support toward and from the axis of the stock until the zero point on the fixed arm 24 registers with the indication on the scale 22 which shows the desired dimension. Fig. 1 of the drawings shows the feeler support adjusted 25 for reducing the stock to one inch. It is to be understood, of course, that the spaces of the graduations on this scale carried on the side by the support are one-half of the ultimate diameter of the stock, that is, if the 30 stock is to be reduced to one inch and it is circular, the cutter or grinder is fed toward the axis of the stock but one-half of an inch. If the stock is to be reduced to a few thousandths, or ten-thousandths, more or less than is indicated on the scale 22 mounted on the carriage, the hand wheel is turned so that the scale 10 on its periphery indicates with relation to zero on the arm 11 the amount the screw must be rotated in order to 35 effect this difference. The feeling point is now bearing against the stock. When the stock is larger than the ultimate dimension, the upper end of the feeling lever is raised so that the contact lever is free, and the 40 electrical contacts are separated. As the stock is reduced, the upper end of the feeling lever moves downward until the time when the stock reaches the required dimension.

Then the end of the set screw carried by the 45 upper end of the feeling lever forces down

the contact end of the contact lever and causes the electrical contacts to engage and close the circuit. This sets in action the apparatus which causes the reducing tool or agent to cease its work.

If the point of the feeling lever becomes worn, or in case there are any irregularities in the manufacture of the apparatus, or whenever a new point is inserted, and the feeling point is not in the correct position 70 to cause the reducing agent to stop work at the exact dimension required, the clamp lever 17 is loosened and the nut handle is turned either one way or the other, the amount of which is indicated by the scale 19 80 on the nut, so as to move the support in or out along the feed screw. By this means, no matter from what cause the feeling point varies, the carriage can be adjusted so that the feeling point will act accurately, and the 85 scales read correctly.

The invention claimed is:

1. In a dimensioning apparatus, the combination with a feeler movably mounted and adapted to engage stock to be reduced, of a 90 movably mounted support for the feeler, means for moving the support toward and from the stock, and adjustable means connecting the said support and the said support moving means for determining the relation 95 of the support to the moving means.

2. In a dimensioning apparatus, the combination with a feeler movably mounted and adapted to engage stock to be reduced, of a 100 movably mounted support for the feeler, a feed screw for moving the support toward and from the stock, and adjustable means connecting the said support and the said feed screw.

3. In a dimensioning apparatus, the combination with a feeler movably mounted and adapted to engage stock to be reduced, of a 105 movably mounted support for the feeler, a feed screw for moving the support toward and from the stock, a hand wheel for turning 110 the feed screw, a scale mounted upon the hand wheel, an index co-operating with said scale, and adjustable means carried by the feeler support and engaging the feed screw 115 for adjusting the position of said support with relation to the said screw.

4. In a dimensioning apparatus, the combination with a feeler movably mounted and adapted to engage stock to be reduced, of a 120 movable support for the feeler, means for moving the support toward and from the stock, means for adjusting the support with relation to said moving means, and means for clamping said adjusting means.

5. In a dimensioning apparatus, the combination with a feeler movably mounted and adapted to engage stock to be reduced, of a 125 movably mounted support for the feeler, a feed screw for moving the support toward and from the stock, a hand wheel for turning 130

the feed screw, a scale mounted on the hand wheel, an index registering with said scale, a scale carried by said support, an index registering with the scale carried by the support, and adjustable means connecting the feed screw and said feeler support.

6. In a dimensioning apparatus, the combination with a feeler movably mounted and adapted to engage stock to be reduced, of a movably mounted support for the feeler, a nut carried by the support, means for rotating the nut, means for clamping the nut, and a feed screw turning in said nut for moving the feeler support toward and from the stock.

7. In a dimensioning apparatus, the combination with a feeler movably mounted and adapted to engage stock to be reduced, of a movably mounted support for the feeler, a nut movable in the support, means for clamping the nut to said support, a scale carried by the nut, an index carried by the support and coöperating with said scale, and a feed screw engaging said nut and adapted, through the nut, to move the support toward and from the stock.

8. In a dimensioning apparatus, the combination with a feeler movably mounted and adapted to engage stock to be reduced, of a

movably mounted support for the feeler, means for moving the support toward and from the stock, an adjustable connection between said moving means and the support, and electrical contacts carried by the support and adapted to be closed by the feeler when the stock is reduced to the predetermined dimension.

9. In a dimensioning apparatus, the combination with a feeler movably mounted and adapted to engage stock to be reduced, of means for moving the feeler toward the stock, and adjustable means connecting said moving means with said feeler.

10. In a dimensioning apparatus, the combination with a feeling point adapted to engage the stock to be reduced, of a lever carrying said point, a movably mounted support bearing said lever, means for moving the support toward and from the stock, and an adjustable connection between said moving means and said support, whereby the relative position of the feeling point to the supporting means may be accurately determined.
